UNITED STATES PATENT OFFICE.

CLARENCE E. LOMAX, OF CHICAGO, ILLINOIS, ASSIGNOR, BY MESNE ASSIGNMENTS, TO AUTOMATIC ELECTRIC INC., OF CHICAGO, ILLINOIS, A CORPORATION OF DELAWARE.

TELEPHONE SYSTEM.

Application filed May 16, 1921, Serial No. 469,909. Renewed January 5, 1927.

The present invention relates in general to telephone systems, but more especially to private branch exchange systems, and in particular to a type of branch exchange which is adapted for use by the fire and police departments of a large city. In such systems the service requirements are very exacting, and a combination automatic and manual branch exchange system has been designed, therefore, with a view to providing a system of maximum reliability, which at the same time takes care of all the different operating requirements.

The various features of the invention will be pointed out and described hereinafter with reference to the accompanying drawings, comprising Figs. 1, 2, and 3, which show by means of the usual circuit diagrams a fire and police system embodying the principles of the invention.

Referring to the drawing, the system therein depicted is a 100 line branch exchange which is interconnected with a manual main exchange by a group of trunk lines. In Fig. 1 one of these interconnecting trunk lines, comprising conductors 20 and 21, is shown extending from the jack J in the main exchange to the plug ending cord circuit O in the branch exchange. The main exchange equipment is old and only enough of it is shown to enable the operation to be explained. The cord circuit O, it will be understood, is used to connect the associated trunk line with local lines in the branch exchange. In the lower half of Fig. 1 one of the branch exchange operators local cord circuits is shown and is indicated by the reference character O'. This cord circuit is used for completing local connections when the branch exchange is being operated as a manual exchange.

In Fig. 2 one of the local stations is shown and is indicated by the reference character A. The substation A is an automatic substation of the usual type and is provided with a calling device for controlling the automatic switches when the system is operating as an automatic system. The line conductors 101 and 102 extend through contacts in the relay equipment associated with the multiple jack J², by way of conductors 110 and 112 to the relay equipment associated with the answering jack J', and thence through certain contact springs to line con-

ductors 130 and 133 which terminate in the individual line switch C. The line switch C is a line switch of the Keith or plunger type, and together with the other individual line switches is controlled by the master switch MS.

The subscribers' individual line switches, such as the line switch C, Fig. 2, have access to a group of trunk lines terminating in the local connectors, which are of the well known Strowger vertical and rotary type. One of these trunk lines is shown in the drawing and comprises conductors 158, 159, and 160, which extend to and terminate in the local connector H, Fig. 3. This local connector is of the connector selector repeater type, by which is meant a connector switch which on certain levels operates as an ordinary connector for completing local connections, while on another level, known as the trunking level, it operates as a selector to automatically select an idle trunk line. When operating on this trunking level when an idle trunk line is selected, the circuits in the connector are altered so as to complete a bridge across the selected trunk line. The closure of the bridge across the trunk line serves to actuate a signal at the distant manual exchange, and since the bridge is under the control of the line relay of the local connector if the main exchange is of the automatic type, instead of the manual type, the local connector is now adapted to operate as a repeater to control automatic switches in the main exchange. Hence the name connector selector repeater.

As stated hereinbefore, the branch exchange system may be operated either as an automatic system or as a manual system. The position of the key K⁴ in Fig. 2 is what determines the character of the system. With this key in its normal position, as shown in the drawing, the system is adapted for automatic operation, while if the key is actuated and left in operated position the automatic equipment is removed from the control of the calling subscribers and the system will operate as a manual system. For convenience in describing the various features of the invention, which will now be proceeded with, it will be assumed first that the system is operating automatically.

The process of establishing a local connection will first be explained and for this pur-

pose it will be assumed that the subscriber at substation A, Fig. 2, wishes to obtain connection with the subscriber at substation A', Fig. 3. When the receiver is removed a circuit is completed for the line relay 140 of the individual line switch C and for the line relay 115 associated with the answering jack J' which may be traced as follows: from ground at the individual line switch 10 C by way of cut off springs 146 and 145, conductor 130, resting contact of armature 120 and the said armature, conductor 110, resting contact of armature 107 and the said armature, line conductor 101, the calling device, transmitter and receiver at substation A, line conductor 102, armature 109 and its resting contact, conductor 112, armature 122 and its resting contact, conductor 133, cut off springs 143 and 144 and through 15 the windings of relays 140 and 115 in parallel to battery. Upon the closure of the foregoing circuit, relays 140 and 115 are both energized and the former relay upon attracting its armature closes a circuit for the 20 pull down winding 141 of the line switch C. The pull down winding is at once energized and operates both the cut off armature 147 and the plunger arm 148, the former being effective to separate the cut off springs 143 and 145 from springs 144 and 146, respectively, while the latter is effective to force 25 the bank springs 150, 151, 152, and 153 into engagement with bank contacts 154, 155, 156, and 157, respectively. By the separation of 30 the cut-off springs the energizing circuit for line relays 140 and 115 is broken, and relay 115 at once falls back. Relay 140, however, is slow acting and retains its armature attracted for a brief interval, long enough for 35 a holding circuit to be established at the connector H, as will be described. By the engagement of bank springs 150 and 153 with bank contacts 154 and 157 the calling line is extended by way of trunk conductors 40 158 and 160 to the line relay 200 of the connector H, and the said line relay is at once energized over the calling subscriber's line circuit. On attracting its armature 217, relay 200 closes a circuit for the slow acting 45 release relay 201, which upon energizing prepares the switch for its vertical operation at armature 218 and at armature 219 connects ground to the release trunk conductor 159. By the latter operation, a holding circuit for 50 the line switch C is completed which extends by way of the now grounded armature 219 of relay 201, release trunk conductor 159, bank contact 155, bank spring 151 and through the holding winding 142 of the line 55 switch C to battery. The energization of the holding winding 142 serves to maintain the cut off armature 147 and the plunger arm 148 in operated position. A branch of the holding circuit extends by way of conductor 60 131 and armature 121 and its resting 65

contact to the winding of relay 116 associated with the answering jack J', and this relay is accordingly energized to open the circuit of relay 117. Another branch extends by way of conductors 131 and 111 and armature 108 and its resting contact to relay 104 which is associated with the multiple jack J². Relay 104 accordingly energizes and opens the circuit of relay 105. By the energization of relay 116 and 104 the operator or operators are prevented from listening in on the call, or from interfering with it in any way whatsoever. In order to notify the operators that the line is in use, the busy lamps L⁵ and L⁷ are provided which are connected with conductors 131 and 111, respectively, and which are, therefore, lighted at this time. There is still another branch of the holding circuit which extends by way of conductor 181 to test contact 264 and its multiples in the banks of the local connector switches, where by a ground potential on these test contacts the line of substation A is made busy. The operation of the line switch C is, of course, followed immediately by the operation of the master switch MS. When the bank spring 152 engages bank contact 156 ground is placed on conductor 161 extending to a contact in the master switch bank and a circuit is completed for the starting relay 163. Upon energizing, the latter relay closes a circuit for the locking magnet 164. Upon energizing, the locking magnet unlocks the master switch shaft and closes a circuit for the motor magnet in order to advance the shaft and re-align the plungers of the idle line switches in front of an idle trunk line, while at the same time the open main conductor 162 is disconnected from the negative pole of the battery in order to prevent the operation of any line switch while the master switch is in operation.

The calling line has now been extended through to the connector H, which is ready 110 for the reception of impulses produced by the calling device at the calling station. When the calling device is operated in accordance with the first digit in the number at substation A', a series of interruptions is produced in the circuit of the line relay 200 and the line relay accordingly deenergizes a like plurality of times, sending at each deenergization an impulse of current 115 through the vertical magnet over the following path: from the grounded armature 217 by way of the resting contact of said armature, armature 218 and its working contact, off normal springs 215 and 213, winding of the slow acting series relay 202 and the winding of the vertical magnet 210 to battery. By the operation of the vertical magnet the switch shaft is raised step by step until the wipers 260, 261, and 262 stand 120 opposite the horizontal level of bank con- 125

tacts in which the line of substation A' is terminated. Relay 202 is energized in series with the vertical magnet and being slow acting remains in operated position during the vertical operation of the switch. The operation of armature 221 of relay 202 is of no consequence at this time, but at armature 220 the vertical magnet circuit is maintained closed notwithstanding the shifting of the off normal springs, which occurs at the first vertical step of the switch. At the end of the vertical operation relay 202 falls back and at its armature 220 transfers the operating circuit to the rotary magnet 211. The calling subscriber may now operate his calling device in accordance with the second and final digit in the number. As a result another series of interruptions is produced in the circuit of the line relay 200 which responds as before and sends a series of impulses to the rotary magnet over the following path: from the grounded armature 217 by way of the resting contact of said armature, armature 218, and its working contact, off normal springs 215 and 214, armature 220 and its resting contact, normally closed contact springs controlled by armature 235, armature 242 and its resting contact and the winding of the rotary magnet 211 to battery. By the operation of the rotary magnet the switch shaft is rotated step by step until the wipers 260, 261, and 262 are finally brought to rest in engagement with the particular set of bank contacts in which the line of substation A' is terminated, these contacts being indicated in the drawing by reference numerals 266, 267, and 268. The slow acting relay 207 is energized in parallel with the rotary magnet and remains in operated position throughout the rotary movement of the switch. The circuit change produced by armature 236 of relay 207 need not be considered at the present time. At armature 237, relay 207 connects test wiper 261 with the winding of the test relay 206, while at armature 238 a shunt is placed around the normally closed contact controlled by armature 235 of relay 206, the latter operation being effective to maintain the rotary magnet circuit closed in case the test relay 206 should be operated by the engagement of test wiper 261 with grounded test contacts during the rotation of the switch.

Assuming first that the line of substation A' is busy when called, when the test wiper 261 comes to rest in engagement with test contact 267 it will find a ground potential and the test relay 206 will be energized. Upon energizing, the test relay opens the rotary magnet circuit at armature 235, opens the circuit of the switching relay 208 at the back contact of armature 234, closes a locking circuit for itself at the working contact of the said armature 234, and at

armature 233 connects a lead coming from the busy signalling machine to the lower side of the trunk line incoming to the connector switch. By this operation an audible busy signal is transmitted to the calling subscriber, who is thus notified that the called line is engaged and is, therefore, inaccessible for the time being.

Having described the operation which takes place when the called line is busy, it will now be assumed that the line is idle when called. Under these circumstances when the test wiper 261 comes to rest in engagement with test contact 267 it will find no ground potential and the test relay 206 will not be energized. Then when the slow acting relay 207 falls back an instant later a circuit is completed for the switching relay 208 which extends from the grounded release trunk conductor 159 by way of armature 234 and its resting contact, upper winding of the switching relay 208, resting contact of armature 237 and the said armature, normally closed contact springs controlled by armature 240, test wiper 261, test contact 267, conductor 291 and through the holding winding 295 of the line switch individual to the line of substation A' (not shown) to battery. The holding winding 295 is energized and by operating the cut off armature of the line switch clears the line of its normal battery and ground connections in the usual manner. It will be understood that the line equipment which is associated with the line of substation A' is the same as the line equipment which is associated with substation A, and since this line equipment is quite complicated it has not been considered advisable to show it completely since to do so would involve a mere duplication of Fig. 2. The essential circuits involved when the line is called are shown however. Relays 293 and 294 correspond to relays 116 and 104 in Fig. 2 and are energized to break the circuits of the relays corresponding to relays 117 and 105 in order to prevent the possibility of interference by the operator. It will be understood also that the busy lamps which are associated with the called line are lighted in order to notify the operator that the line is in use. In the connector H, when switching relay 208 is energized it establishes a locking circuit for itself at armature 241, opens the rotary magnet circuit at armature 242, connects ground to the test wiper 261 at armature 240, and at armatures 239 and 243 connects up the upper and lower line wipers 260 and 262. A signal circuit is now established over which ringing current from the generator GEN is projected intermittently out over the called line in order to operate the bridged ringer at substation A' and notify the subscriber that he is wanted at the telephone. The upper winding of the ring cut-off relay

205 is included in the signalling circuit and when the called subscriber answers by removing his receiver relay 205 is operated, establishing a locking circuit for itself at armature 231. In addition, relay 205 opens the signalling circuit at armatures 230 and 232 and at the working contacts of these armatures finally completes the talking connection. After the ring cut-off relay 205 is operated the back bridge relay or impedance coil 203 is bridged across the called line in series with the battery in order to supply talking current to the transmitter at the called station. The calling station is, of course, supplied with talking current through the windings of the line relay 200, and since the connection is now completed the subscribers may converse together as desired.

When the subscribers are through talking, they will both replace their receivers. The release of the connection is brought about by the replacement of the receiver at the calling station A, which causes the line and release relays 200 and 201 of the connector H to be deenergized. On retracting their armatures, these relays jointly close a circuit for the release magnet 212 which restores the connector H to normal position in the well known manner. Relay 201 also disconnects ground from the release trunk conductor 159, thus breaking the locking circuits of relays 205 and 208. This operation also breaks the holding circuit extending back over the release trunk conductor to the line switch C, and the holding winding 142 is deenergized to permit the restoration of the line switch. At the same time relays 116 and 104, associated with the answering and multiple jacks J¹ and J², respectively, are deenergized, and the calling line is thus returned to normal condition ready to make another call, or be called. The called line, of course, is cleared by the release of the connector H which removes ground from the conductor 291, thus deenergizing all the relay windings associated with the called line which had been energized during the conversation.

Having described the process of setting up a local connection, the manner in which a connection is extended to the main exchange will now be described, it being assumed that the subscriber at substation A desires to obtain connection with some subscriber whose line terminates in the main exchange. When the receiver is removed at substation A the same operations which were described before take place and the calling line is extended by means of the individual line switch C to an idle local connector, which we will assume to be the connector H. The main exchange trunk lines are terminated in the tenth level of the local connector and in order to obtain access to these trunk lines, therefore, the calling subscriber will have to operate his calling de-

vice in accordance with the digit 0. The connector switch responds in the manner before described and the vertical magnet 210, under the control of the line relay, raises the switch shaft step by step until the 70 wipers stand opposite the tenth level of bank contacts. When the switch shaft arrives at the tenth level, the cup spring easing mounted on the top of the shaft engages the shaft spring 225 and springs 225 and 227 are brought into engagement with their working contacts. As a result a circuit is closed at spring 225 which includes the winding of relay 204 and the upper winding of the ring cut-off relay 205 in 80 series. Both these relays are energized and relay 204 disconnects the exchange battery from the windings of the impedance coil 203 and connects the inner terminals of the two windings together. Slow acting series 85 relay 202 is energized in series with the vertical magnet and consequently when the shaft spring 227 engages its working contact on the arrival of the shaft at the tenth level relay 202 will be energized and a circuit will be closed for the test relay 206, which may be traced from the release trunk conductor 159 by way of spring 227 and its working contact, armature 221 and its working contact, the interrupter contact of the 90 rotary magnet 211 and the winding of test relay 206 to battery. Upon energizing, relay 206 establishes a locking circuit for itself at armature 234, and at armature 235 prepares a circuit for the rotary magnet 211. 100 At the end of the vertical movement of the switch the slow acting relay 202 deenergizes and at armature 221 closes a circuit for the rotary magnet which extends from the grounded release trunk conductor 159 by 105 way of spring 227 and its working contact, armature 221 and its resting contact, armature 235 and its working contact, armature 242 and its resting contact and the winding of the rotary magnet 211 to battery. Upon 110 the closure of the above circuit, the rotary magnet is operated and rotates the switch shaft one step to bring the wipers into engagement with the contact set in which the first trunk line is terminated. The slow 115 acting relay 207 is energized in parallel with the rotary magnet 211 and at armature 237 connects the test wiper 261 to the circuit of the test relay 206. When the rotary magnet energizes and rotates the switch wipers into 120 engagement with the first trunk line, it also opens its interrupter contact and breaks the circuit of the test relay 206, which accordingly falls back and at armature 235 breaks the circuit of the rotary magnet and the circuit of the slow acting relay 207. The rotary magnet at once deenergizes and again 125 closes its interrupter contact, but relay 207 being slow acting remains in operated position for an instant and retains the test wiper 130

261 in connection with the test relay. The interrupter contact of the rotary magnet now being closed, if the first trunk line is busy the test wiper will find a ground potential on the test contact with which it is in engagement and the test relay 206 will again energize, close its locking circuit, and again close the circuits of the rotary magnet 211 and the slow acting relay 207. The rotary magnet is, therefore, again operated and the switch wipers are rotated into engagement with the second contact set. It will be seen that the rotary magnet 211 and the test relay 206 will continue to operate alternately in this manner as long as the test wiper 261 continues to engage busy or grounded test contacts, relay 207 remaining in operated position meanwhile to retain the test wiper in connection with the circuit of the test relay 206. As soon as an idle trunk line is reached, which we will assume to be the trunk line shown in the drawing and comprising conductors 70, 71, and 72, test wiper 261 will find no ground potential on the test contact 270 and the test relay 206 will fail to pull up on the last deenergization of the rotary magnet 211. The rotary movement of the switch will accordingly cease and when the slow acting relay 207 falls back an instant later a circuit is completed for the upper winding of the switching relay 208, which may be traced as follows: from the grounded release trunk conductor 159 by way of armature 234 and its resting contact, upper winding of the switching relay 208, resting contact of armature 237 and the said armature, normally closed contact springs controlled by armature 240, test wiper 261, test contact 270, conductor 71, armature 49 and its resting contact, winding of relay 30, and the winding of relay 32 to battery. Upon the closure of the above circuit relay 208 is energized in series with relays 30 and 32 and performs the same functions in the connector H as were described in the case where a connection was extended to the line of substation A'. In the cord circuit O, relays 30 and 32 are energized and the former relay at armature 41 disconnects the sleeve relay 35, while at armatures 40 and 42 the conductors 20 and 21 of the trunk line are disconnected from the tip and ring strands of the cord circuit. The energization of relay 30 thus completely separates the conductors of the trunk line from those of the cord circuit O and prevents the operator from interfering with the connection in any way. The trunk line having been disconnected from the cord circuit it will be seen that the polar relay 33, which in the normal idle condition of the trunk line is energized by current supplied through the windings of the line relay 15 at the main exchange, will be cut off from its source of

current, and its armature will be shifted under the influence of the retractile spring. Relay 34 is not energized, however, because relay 32, which is now energized, has disconnected ground from the polar relay armature at armature 46. In order to notify the branch exchange operator that the trunk line is in use, the busy lamp L² is now lighted over a branch extending from the grounded conductor 71. 70 75

The connection to the main exchange trunk line has now established and the trunk line has been properly isolated for the sole use of the calling subscriber. The main exchange operator is signalled automatically without further act on the part of the calling subscriber by the operation of the line relay 15 at the distant end of the trunk line. This line relay energizes in series with the impedance coil 203 which is now connected in bridge of the connector line wipers 260 and 262. Upon energizing, line relay 15 lights the line lamp L, which notifies the main exchange operator that a call has been received. The operator answers by plugging into the jack J and completes the connection to the desired local line with one of her cord circuits in the usual and well known manner. 80 85 90

The release of the connection is under the control of the branch exchange subscriber who by replacing his receiver can release the connector H in the same way as was described in the case of the local connection. 95

An inter-exchange connection in reverse direction, or from the main exchange to the branch exchange, will now be described briefly and for this purpose it will be assumed that some subscriber in the main exchange is calling a party at substation A in the branch exchange. At the main exchange the operator who handles the call will plug into an idle trunk line extending to the branch exchange and we will assume that the trunk line comprising conductors 20 and 21 is the one taken for use. The polar relay 33 is normally bridged across the two conductors of the trunk line at the cord circuit O and is energized by current flow through the windings of the line relay 15 in such direction that it maintains its armature in the position shown in the drawing, the resistance of the polar relay being sufficiently high to prevent the line relay 15 from operating. Now, when the main exchange operator plugs into the jack J line relay 15 is disconnected from the trunk line, and current is supplied to the trunk line from the cord circuit. The arrangement is such that when the operator plugs in current flow over the trunk line is reversed, as will be understood by the partial showing of the main exchange operator's cord circuit which is indicated by the reference character O². The cord circuit may be of 100 105 110 115 120 125 130

any well known common battery type and the incomplete circuit arrangement shown is intended merely to indicate the arrangement for reversing the battery when the 5 plug is inserted in the jack. To proceed, when the direction of current flow over the trunk line is reversed polar relay 33 responds by shifting its armature and a circuit is completed for the slow acting relay 10 34. Upon energizing, relay 34 disconnects conductor 71 from the winding of relay 30 and connects it to ground instead. By this 15 operation a ground potential is placed upon the test contact 270 and its multiples in the banks of the local connectors and the trunk line is made busy. At the same time the busy lamp L^2 is lighted to notify the attendant operator at the branch exchange that the trunk line is in use.

20 The main exchange operator will now ring over the trunk line in order to operate the relay 31, the lower winding of which is connected across the trunk line at the cord circuit in the branch exchange. Upon energizing, relay 31 establishes a locking circuit for itself at armature 44 and at armature 43 closes a circuit for the call signal lamp L^1 . The lighting of this lamp signals the operator at the branch exchange. The operator 25 answers the call by throwing the listening key K which opens the two strands of the cord circuit and connects her head set in bridge of the conductors of the trunk line. Although current to the polar relay 33 is 30 interrupted by this operation, the armature of the polar relay remains in its shifted position under the influence of the retractile spring and relay 34 remains energized. When the attendant operator's head set is 35 bridged across the trunk line a current flow is established which operates the supervisory relay in the main exchange operator's cord circuit and extinguishes the supervisory lamp. The main exchange operator will 40 now respond and advise the operator in the branch exchange of the number of the party desired.

Having received the required information, the operator at the branch exchange will 45 plug into the jack at her position which is associated with the desired line. This may be the jack J' , or the jack J^2 , but assuming that the jack J' is the one in which the plug associated with the cord circuit O is inserted, 50 upon the insertion of the plug in the jack a circuit is completed over the sleeve of the cord for the sleeve relay 35. Upon energizing, relay 35 connects relay 36 in bridge of the two strands of the cord circuit at armature 55, prepares a circuit for the trunk 55 supervisory lamp L^3 at armature 54, and at armature 52 closes a circuit for relay 32. Upon energizing, relay 32 opens the locking circuit of relay 31 and disconnects the lower winding of this relay from in bridge of the

cord circuit, these operations being performed at armatures 45 and 47, respectively. In addition, relay 32 disconnects ground from the polar relay armature at armature 46, but this causes no harm for the polar relay armature is maintained grounded at armature 53 of relay 35.

Considering now the effect on the line equipment of the called line, when the trunk plug is inserted in jack J' a circuit is completed in an obvious manner for relay 117 which energizes and at armatures 120 and 122 disconnects conductors 110 and 112 from conductors 130 and 133 and connects them instead with the tip and ring springs of the jack J' . This operation disconnects the called line from the individual line switch C . Relay 117 also connects ground to conductors 131 and 111. By the latter operation the busy lamps L^5 and L^7 are lighted, the latter lamp being useful in indicating to the operator at the multiple position that the line is in use. The grounding of conductor 131 energizes the cut-off winding 142 of the line switch C , resulting in the operation of the cut-off armature 147. Ground is also extended over the branch including conductor 181 to test contact 264 and its multiples in the banks of the connectors in order to make the called line busy. By the grounding of conductor 111, relay 104 is energized and this relay operates to disconnect relay 105. This is done in order to prevent the operator at the multiple position from listening in on the connection.

The branch operator may now restore key K to normal position, and throw key K' to ringing position momentarily in order to project ringing current out over the called line. When key K is restored the trunk line is connected through to the upper and lower strands of the cord circuit and relay 36 which is connected in bridge of the cord circuit is accordingly energized. Current flow through the winding of relay 36 serves to maintain the supervisory relay in the main exchange cord circuit operated and keeps the supervisory lamp extinguished while at the branch exchange the energization of relay 36 lights the local supervisory lamp L^4 .

When the called subscriber answers by removing his receiver, his transmitter is supplied with talking current from the cord circuit at the main exchange. This energizes relay 37 which is included in the upper strand of cord circuit O at the branch exchange and disconnects relay 36 from in bridge of the cord circuit. Upon deenergizing, relay 36 extinguishes the supervisory lamp L^4 in order to notify the branch operator that the local subscriber has answered. The complete connection has now been established and the subscribers may converse as desired. When the conversation is finished both parties will hang up their re-

ceivers. The replacement of the receiver by the main exchange subscriber, of course, gives the main exchange operator disconnect supervision at the local end of her cord circuit in the usual manner. When the branch exchange subscriber at substation A hangs up, relay 37 is deenergized, relay 36 is thus again connected in bridge of the two strands of the cord circuit O and is operated to again light the local supervisory lamp L⁴ and give the branch exchange operator a disconnect signal. If the branch exchange operator pulls the connection down first the relay 35 will be deenergized and relay 36 will be disconnected from in bridge of the cord circuit, thus leaving only the high resistance relay 33 across the line. Relay 33 is in such high resistance that the supervisory relay of the main exchange cord circuit will fall back and give the operator a disconnect signal on the trunk end of her cord. In case the main exchange operator should pull down the connection first, line relay 15 is again connected in bridge of the trunk line and the current flow through the winding of the polar relay 33 is reversed. Relay 33 accordingly operates to shift its armature into normal position, as shown in the drawing, and a circuit is completed for the trunk supervisory lamp L⁵, which is lighted to give the branch operator a trunk disconnect signal. In either case it will be seen that when the subscribers hang up their receivers each operator gets a local disconnect signal, while the last operator to pull down the connection receives a trunk disconnect signal in addition to the local disconnect signal which indicates to her that the other operator has pulled down the connection.

In case the branch operator should find it necessary to talk to the local subscriber while the trunk plug is inserted in the jack at any time, the key K' may be thrown to listening position in order to bridge the operator's head set across the tip and ring conductors of the plug. Since the operation of the listening key opens the two strands of the cord circuit the supply of talking current to the local subscriber from the main exchange will be cut off, and retard coils 38 and 39 are provided, therefore, in order to supply talking current to the local substation under these circumstances. It will be noted that both of the listening keys K and K' operate to open the conductors of the cord circuit. The circuit is arranged in this way in order to prevent the branch operator from listening in on any connection after the same is established.

In order to complete the explanation it will be assumed now that it is desired to operate the branch exchange as a manual system. The change from automatic to manual operation is effected by actuating

the key K⁴, shown in Fig. 2, which is of the self locking type and which will remain in operated position when actuated until it is manually restored to normal. This key is included in the open main conductor 162 and in operated position is effective to disconnect the pull down windings of all the individual line switches, such as the line switch C, from the negative pole of the branch exchange battery. Assuming that the key K⁴ is in operated position, then the process of obtaining a connection from the local substation A may be considered briefly. When the receiver is removed circuits are completed, as in the case previously described, for the line relay 140 of the individual line switch C and for the line relay 115 associated with the answering jack J'. Both relays are energized but now the energization of the line relay 140 is without effect for the battery is disconnected from the pull down winding 141 and the line switch C, therefore, cannot be operated. It follows, therefore, that the line relay 115 will remain energized and will light the call signal lamp L⁶ in order to notify the branch operator that a call has been received. On perceiving the signal, the operator will answer the call by inserting the answering plug of one of her local cord circuits, the cord circuit O' for example, in the jack J'. As a result relay 117 is energized and the line conductors 101 and 102 of the calling line are connected with the tip and ring strands of the jack. Relay 117 also grounds conductors 131, 181, and 111 with results which may be briefly pointed out. By the grounding of conductor 131 the busy lamp L⁵ is lighted and the holding winding 142 of the line switch C is energized. This operates the cut-off armature 147 and disconnects the line relay 140. By the grounding of conductor 181 the called line is made busy in the banks of the local connectors. This operation is, of course, of no particular effect unless it should happen that the key K⁴ is restored to normal position and the system is changed back to an automatic system before the connection in question is terminated. By the grounding of conductor 111 the busy lamp L⁷ is lighted at the multiple position, and relay 104 is energized. The operation of relay 104 opens the circuit of relay 105 and prevents the operator at the multiple position from interfering with the connection.

In case a local connection is desired, the calling plug of the local cord circuit in use is inserted in the jack associated with the desired line, and the desired connection is thus completed. The local cord circuit O' is a well known type of cord circuit and it is so extremely simple that it is believed to be unnecessary to go into any further details.

In case the local subscriber at substation A

desires a trunk connection to the main exchange, the answering plug of the local cord circuit will be withdrawn and the trunk plug associated with an idle main exchange 5 trunk line will be substituted therefor. The operation of completing the connection from the local substation to the desired station in the main exchange will then take place substantially as was described in the case where 10 a main exchange subscriber was calling a branch exchange subscriber, except that certain of the operations take place in the reverse order. It may be stated that the branch exchange operator is able to signal 15 the operator at the main exchange by throwing the listening key K, which bridges her head set across the trunk line and operates the line relay 15 at the main exchange.

Although as stated hereinbefore the 20 branch exchange system shown herein is a 100 line system, it will be understood that the size of the system may be increased to any desired extent by inserting selector switches between the individual line switches and the 25 local connectors according to well known practice. If the size of the system is thus increased to a considerable extent it will make it necessary to use several multiple positions in addition to the usual answering 30 position, and it is chiefly on this account that the circuit arrangements for wiring the multiple positions have been shown in Fig. 2. It should be understood, however, that under certain circumstances a multiple position 35 may be used even in a 100 line system, for the conditions under which the system is operating may be such as to require two switchboards which are located at different points, all of the subscribers' lines being 40 multiplied in both switch-boards.

Attention is directed also to an advantage which is secured by the particular scheme employed for changing the system from automatic to manual operation. Inasmuch 45 as the key which is used for this purpose accomplishes the desired object by opening the open main conductor, it will be seen that whenever this conductor is opened by the master switch in the ordinary operation of 50 the system as an automatic system, as when all the outgoing trunk lines are busy, the system will for the time being be changed automatically to a manual system independent of the actuation of the key. In other 55 words, if a subscriber makes a call when all the local connectors are busy, he will signal the operator, while if any connector is available it will be taken for use and the operator will not be signalled.

60 Having described my invention, what I consider to be new and desire to have protected by Letters Patent will be pointed out in the appended claims.

What I claim as my invention is:

65 1. In a combined automatic and manual

telephone system, subscriber controlled automatic switches for connecting calling and called lines, operator's manual equipment for connecting calling and called lines, and operator controlled means for causing the 70 system to operate as an automatic system or as a manual system at will.

2. In a combined automatic and manual telephone system, subscriber controlled automatic switches for connecting calling and called lines, operator's manual equipment for connecting calling and called lines, and a centrally located device operable at will to cause the system to operate as an automatic system, or as a manual system. 75 80

3. In a combined automatic and manual telephone system, subscriber controlled automatic switches for connecting calling and called lines, operator's manual equipment for connecting calling and called lines, and a key at an operator's position for determining whether the system is to operate automatically or manually. 85

4. In a telephone system, subscribers' lines, subscriber controlled automatic switches for connecting calling and called lines, operator's manual equipment for connecting calling and called lines, the automatic equipment being normally operative responsive to calls and the manual equipment being normally 90 inoperative, operator controlled means for rendering the automatic equipment inoperative, and circuit arrangements such that the manual equipment is automatically rendered operative when the automatic equipment is 95 rendered inoperative. 100

5. In a telephone system, a subscriber's line and a manual jack individual thereto, an automatic switch for extending said line when calling, a signal associated with said jack, means for operating said signal responsive to a call, means for preventing the operation of said signal when said switch is operated responsive to a call, and means for preventing the operation of said switch responsive to a call in order to permit said signal to be operated. 105 110

6. In a telephone system, a subscriber's line, a manual jack and an automatic switch individual to said line, a cut-off relay for disconnecting the operating and connecting elements of the switch from the line when the operator plugs into said jack, and a second cut-off relay controlled by said switch for disconnecting the said first cut-off relay. 115

7. In a telephone system, a subscriber's line, a manual jack and an automatic switch individual to said line, said jack being normally disconnected and the said switch being normally connected, a line relay and a cut-off relay for said switch, a second cut-off relay for disconnecting the switch and its line relay and for connecting the jack when the operator plugs into the jack, and another relay controlled by said switch for 120 125 130

disconnecting the said second cut-off relay.

8. In a telephone system, a subscriber's line, a manual jack and an automatic switch individual to said line, the tip and ring 5 springs of said jack being normally disconnected and the corresponding contact elements of the said switch being normally connected, a relay for disconnecting the switch contact elements and for connecting the springs of said jack when the operator plugs into the jack, and means for preventing the operation of said relay in case the said switch is operated before the operator plugs in.

15 9. In a telephone system, a subscriber's line, a manual call signal and an automatic switch individual to said line, two line relays individual to said line, one controlling said signal and the other controlling said 20 switch and both normally responsive to calls, and means controlled by the line relay which controls the said switch for disconnecting the other line relay.

10. In a telephone system, subscribers' 25 lines, a manual answering jack for each line, trunk lines, automatic switches for extending calling lines to idle trunk lines, means operated by a calling subscriber for signalling the operator in case all of said trunk 30 lines are busy, and means responsive to the seizure of an idle trunk for rendering said signalling means ineffective.

11. In a telephone system, subscribers' 35 lines, a manual answering jack for each line, trunk lines, automatic switches for extending calling lines to idle trunk lines, means operated by a calling subscriber for signalling the operator in case all of said trunk lines are busy, and means responsive to the 40 seizure of an idle trunk for preventing a calling subscriber from signalling the operator in case an idle trunk line is available.

12. In a telephone system, subscribers' 45 lines, a manual jack and an automatic rotary trunk selecting switch individual to each line, a group of trunk lines accessible to said switches, a line signal for each jack, and circuit arrangements whereby a calling subscriber will operate his line switch to connect with an idle trunk line if idle trunks 50 are available and will operate the associated line signal in case all of said trunk lines are busy.

13. In a telephone system, subscribers' 55 lines, manual jacks for said lines, operator's cord circuits for connecting calling and called lines through the associated jacks, subscriber controlled automatic switches for connecting calling and called lines, and 60 means for preventing an operator from connecting with any line when the same is busy either in an automatically established connection or in a manually established connection.

65 14. In a telephone system, subscribers'

lines, manual jacks for said lines, operator's cord circuits for connecting calling and called lines through the associated jacks, subscriber controlled automatic switches for connecting calling and called lines, and 70 means for preventing an operator from connecting with any line when the same is busy either as a calling or as a called line in either an automatically established connection or a manually established connection. 75

15. In a telephone system, subscribers' lines, manual jacks for said lines, operator's cord circuits for connecting calling and called lines through the associated jacks, subscriber controlled automatic switches for 80 connecting calling and called lines, means for preventing an operator from listening in on automatically or manually established connections, and visual signals for notifying the operators when the lines are busy. 85

16. In a telephone system, a subscriber's line, multiple jacks for said line at a plurality of operator's positions, and means individual to said line effective whenever an operator plugs into any one of said jacks for preventing other operators from listening in on the line by way of another one of said jacks. 90

17. In a telephone system, a subscriber's line, multiple jacks for said line at a plurality of operator's positions, each jack being normally disconnected from the line, means for connecting any jack with the line when an operator plugs in, and means for thereafter preventing another operator from connecting another jack with said line by plugging into such other jack. 95

18. In a telephone system, a plurality of telephone lines equipped with automatic substations, subscriber controlled automatic switches for connecting said lines, operator's manual equipment for connecting said lines, and means comprising a switch in the battery feed conductor for certain of said automatic switches for causing the system to 100 operate automatically or manually as desired. 105

19. In a telephone system, a plurality of telephone lines equipped with automatic substations, subscriber controlled automatic switches for connecting said lines, operator's manual equipment for connecting said lines, circuit arrangements such that the system is normally operative automatically, there being means controlled by certain of the 110 switches for rendering the system inoperative manually, and means for rendering the said last mentioned switches inoperative to permit the system to operate manually. 115

20. In a telephone system, a plurality of telephone lines equipped with automatic substations, subscriber controlled automatic switches for connecting said lines, operator's manual equipment for connecting said lines, and a single operator controlled switch af- 120 125 130

fecting all the said lines simultaneously for determining whether the system is to operate automatically or manually.

21. In a telephone system, a plurality of telephone lines equipped with automatic substations, subscriber controlled automatic switches for connecting said lines, operator's manual equipment for connecting said lines, and manually operable means consisting solely of elements common to said lines for determining whether the system is to operate automatically or manually.

22. In a telephone system, a subscriber's line, a manual jack and an automatic switch individual to said line, a cut-off relay including an armature and contact springs actuated thereby for disconnecting the line from the talking conductors extending to the switch when the operator plugs into said jack, and a second cut-off relay controlled by said switch for disconnecting the said first cut-off relay.

23. In a telephone system, a subscriber's line, a manual jack and an automatic switch individual to said line, said jack being normally disconnected and the said switch being normally connected, a line relay and a cut-off relay for said switch, a second cut-off relay for disconnecting the switch and its line relay and for connecting the jack when the operator plugs into the jack, and another relay controlled by said switch for disconnecting the said second cut-off relay.

24. In a telephone system, a subscriber's line, a call signal and an automatic switch individual to said line, a pair of line relays individual to said line, one controlling said signal and the other controlling said switch, means for simultaneously operating both of said line relays, and means controlled by the line relay which controls the said switch for disconnecting the other line relay.

25. In a telephone system, a subscriber's line, a manual jack and an automatic switch individual to said line, a cut-off relay for disconnecting the switch when the operator plugs into said jack, a second cut-off relay controlled by said switch for disconnecting the said first cut-off relay, a third cut-off relay for performing functions similar to said first cut-off relay, and a fourth cut-off relay controlled by said first cut-off relay for disconnecting the said third cut-off relay.

26. In a telephone system, a subscriber's line, two jacks individual to said line, a relay associated with each jack for connecting the same to the line, a second relay associated with each jack for opening the circuit of the associated connecting relay, and a circuit for each of said second relays controlled by the non-associated connecting relay.

27. In a telephone system, two exchanges, means including a trunk line and manual connective equipment at each end thereof for handling calls from the first exchange

to the second exchange, means including said trunk line, the manual connective equipment at the first exchange and subscriber controlled switches at the second exchange for handling calls from the second exchange to the first exchange, and means effective whenever the trunk line is in use in a call of the second mentioned class for disconnecting the manual connective equipment in the second exchange from the trunk line.

28. In a telephone system, two exchanges, means including a trunk line and manual connective equipment at each end thereof for handling calls from the first exchange to the second exchange, means including said trunk line, the manual connective equipment at the first exchange and subscriber controlled switches at the second exchange for handling calls from the second exchange to the first exchange, an operator's listening key included in said connective equipment at the second exchange, and means effective whenever the said trunk line is in use in a call of the second mentioned class for opening the trunk conductors at a point between the outgoing section of the trunk and said key so as to prevent the operator from listening.

29. In a telephone system, a jack in one exchange, a plug ending cord circuit in a second exchange, a trunk line extending from said jack to said cord circuit, a sleeve relay in said cord circuit energized when the plug is inserted in the jack of a called line, a polar relay bridged across said cord circuit and controlled by a reversal of current flow over said trunk, and a supervisory lamp associated with said cord circuit and controlled by said two relays jointly.

30. In a telephone system, a jack in one exchange, a plug ending cord circuit in a second exchange, a trunk line extending from said jack to said cord circuit, means including said jack, trunk line, and cord circuit for connecting a calling line in the first exchange with a called line in the second exchange, means in the first exchange for supplying talking current to the called line over said trunk line, an operator's listening key in said cord circuit arranged to open the talking strands thereof and connect the operator's head-set to the section associated with the called line, and means in said cord circuit connected up by the operation of said key for supplying talking current to the called line while the key is in actuated position.

31. In a telephone system, a jack in one exchange, a plug ending cord circuit in a second exchange, a trunk line extending from said jack to said cord circuit, means including said jack, trunk line, and cord circuit for connecting a calling line in the first exchange with a called line in the second exchange, means in the first exchange for supplying talking current to the called

line over said trunk line, two listening keys at said cord circuit for enabling the operator to talk to the calling and called parties, respectively, each key being arranged to open 5 the talking strands of the cord circuit to restrict the talking circuit to the operator and the wanted party, and means associated with the key used to talk to the called party for supplying such party with talking current 10 from the second exchange.

32. In a telephone system, a jack in one exchange, a plug ending cord circuit in a second exchange, a trunk line extending from said jack to said cord circuit, means including 15 said jack, trunk line, and cord circuit for connecting a calling line in the first exchange with a called line in the second ex-

change, means in the first exchange for supplying talking current to the called line over said trunk line, a bridge at said cord circuit 20 closed responsive to the insertion of the cord circuit plug in the jack of the called line to draw current from the talking current supply at the first exchange, for maintaining supervisory conditions at the first exchange, 25 and a relay in series with one strand of said cord circuit beyond the said bridge energized by talking current supplied to the called line when the called party answers in order to open said bridge. 30

In witness whereof, I hereunto subscribe my name this 6th day of May, A. D. 1921.

CLARENCE E. LOMAX.
